(57) **CLAIM**

The ornamental design for a toothbrush, as shown and described.

DESCRIPTION

FIG. 1 is a front-right perspective view of a toothbrush according to a first embodiment of our design; FIG. 2 is a front-left perspective view thereof; FIG. 3 is a rear-right perspective view thereof; FIG. 4 is a rear-left perspective view thereof; FIG. 5 is a front view thereof; FIG. 6 is a rear view thereof; FIG. 7 is a left-side view thereof; FIG. 8 is a right-side view thereof; FIG. 9 is a top view thereof; FIG. 10 is an enlarged bottom view thereof; FIG. 11 is a front-right perspective view of a toothbrush according to a second embodiment of our design; FIG. 12 is a front-left perspective view thereof; FIG. 13 is a rear-right perspective view thereof; FIG. 14 is a rear-left perspective view thereof; FIG. 15 is a front view thereof; FIG. 16 is a rear view thereof; FIG. 17 is a left-side view thereof; FIG. 18 is a right-side view thereof; FIG. 19 is a top view thereof; and, FIG. 20 is an enlarged bottom view thereof.

The stippling on the handle portion of the toothbrush in FIGS. 1-10 represents a surface texturing that is different in appearance than the surface texturing of the non-stippled portions of the toothbrush,
